J. FINLAYSON

CONSTRUCTION OF ENDLESS CONVEYERS

Filed Sept. 23, 1924

UNITED STATES PATENT OFFICE.

JAMES FINLAYSON, OF ARARAT, VICTORIA, AUSTRALIA.

CONSTRUCTION OF ENDLESS CONVEYERS.

Application filed September 23, 1924. Serial No. 739,401.

To all whom it may concern:

Be it known that I, JAMES FINLAYSON, a subject of the King of Great Britain, of Ararat, in the State of Victoria, Commonwealth of Australia, engineer, have invented certain new and useful Improvements in and Connected with the Construction of Endless Conveyers, of which the following is a specification.

10 My invention relates to endless conveyers for raising such materials as stone, grain, coal, sand and the like, in buckets or other holding devices and has for its object the employment in the endless conveyer of wire 15 ropes instead of the usual chains or belts.

According to my invention, the conveyer members, such as buckets or slats, are connected at intervals to a plurality of wire cables or ropes that are endless and pass 20 over pulleys having plain or smooth surfaces and that are preferably provided with upstanding side flanges. The conveyer members are secured to the ropes by special means comprised by a grooved base 25 block, conveniently fashioned to rest upon and be secured to the ropes to move therewith over the pulleys. One way of connecting the blocks in position is by bolts that have specially formed heads that fit against 30 the ropes and press same into the grooves when the nuts are tightened. The base blocks are preferably made of metal but may also be formed of suitable hardwoods.

In the accompanying drawings—
35 Fig. 1 shows in side elevation part of an elevator and conveyer members on a pulley.

Fig. 2 is a transverse section of the base block between longitudinal sections of the bucket and pulley.

40 Fig. 3 is a longitudinal section of the block showing the holding bolts and mode of locking two pairs of ropes into the block.

Fig. 4 illustrates the base block in perspective view, upside down, and
45 Fig. 5 is a like view of one of the holding bolts.

The wire ropes 6 pass over pulleys 7, the upper or carrying pulley being shown in Fig. 1. The pulleys are smooth but are provided on their peripheries with upstanding flanges 8, or like means, to limit the lateral movement of the parts supported thereon. To a pair of parallel ropes or to two or more pairs of the ropes, base blocks 9 are attached by the bolts 10 that pass through the block between each parallel rope of a pair.

In the underside of the block are transverse parallel grooves 11 and between each of the grooves the block is cut away or recessed for its whole width from front to back between the grooves, in which part the hole for the reception of the bolt 10 is placed. The depth of the grooves is sufficient to amply receive the ropes 6 that, while resting on the pulley 8, will leave a slight clearance between the pulley and the block. The bolt 10 is made with a specially fashioned head 12 that flares outwardly at the sides so that, when the bolt is inserted from below the block and passed upwards through it between the parallel ropes and through the bucket 13 of the elevator, its head will come into neat contact with the circular ropes 6. On the nut being tightened on the bolt the head 12 will be pressed intimately against the ropes that, in turn, will be forced up into the grooves 11, thus securing the block to the ropes.

To avoid injuring the ropes carrying a block and to facilitate the passage of a block over a pulley, the underside edges of each block are well rounded off and its underside is slightly curved from front to rear with a radius approximating to that of the pulley over which it passes.

The bucket 13 is likewise held by the bolts 10 and to strengthen its connection with the base block 9 a reinforcing plate 14 is between the nut of the bolt and the bucket floor.

The length of the base blocks varies with the width of the bucket and the nature of the materials to be conveyed and the number of hauling ropes will likewise vary. Thus, for lifting stone, a block, as shown in Fig. 3, and employing two pairs of ropes, would be sufficient, while if grain is to be raised, one pair of ropes might only be necessary, the bucket area being about the same in each instance.

I have found in practice that the blocks, the length of which should be only slightly less than the width of the pulley between the flanges, keep the ropes in position on the plain surface of the pulley. Appreciable economies are also possible in the construction of elevators according to my invention.

I have shown the ropes as being circular in cross section, but if ropes made rectangular in section are available, same may be used in place of the circular ropes. In

such case, the grooves in the base block will be made to accommodate the rectangular ropes and the bolts will be fashioned in the heads to press the ropes into the grooves.

5 Such a head, instead of being flared, as in Fig. 5, might be made to taper to engage with and press the ropes into the grooves.

Having now described my invention what I claim as new and desire to secure 10 by Letters Patent is:—

1. In an elevator of the kind indicated, a pair of endless ropes, plain or smooth pulleys on which the ropes are supported and move, grooved base blocks seating at 15 intervals on and held to the ropes and conveyer members attached to the blocks.

2. In an elevator of the kind described, pairs of endless ropes on smooth flanged pulleys, grooved and recessed base blocks seating at close intervals on the ropes, a 20 bolt having a head shaped to the ropes

between each of a pair of passing upwards through the block and a conveyer member secured to the block and through the same to the ropes by the bolt. 25

3. In an elevator of the kind described, one or more pairs of endless ropes on smooth flanged pulleys, base blocks seating at close intervals on the ropes, parallel grooves in the blocks of a depth slightly 30 less than the thickness of the ropes, a transverse recess between each of the grooves of a pair, a bolt hole in each recess, a bolt having a head to engage and press against each pair of ropes, a conveyer member and a reinforcing plate between such member and the nut of the bolt that secures the parts on a base block and the block to the ropes. 35

In witness whereof I affix my signature.

JAMES FINLAYSON.
